(57) CLAIM

The ornamental design for a display screen or portion thereof with a graphical user interface as shown and described herein.

DESCRIPTION

The sole FIGURE is a front view of a display screen or portion thereof with a graphical user interface of our new design.

The outer perimeter broken lines in the drawings represent a Display Screen or Portion Thereof and forms no part of the claimed design. The remaining broken lines in the drawings illustrate portions of a Graphical User Interface that forms no part of the claimed design.
